CLAIM

The ornamental design for cookware, as shown and described.

DESCRIPTION

FIG. 1 is a perspective view of an embodiment of the present invention;

FIG. 2 is a bottom view thereof;

FIG. 3 is a top view thereof;

FIG. 4 is a back view thereof;

FIG. 5 is a front view thereof;

FIG. 6 is a right side view, the left side view being a mirror image thereof;

FIG. 7 is perspective view of a further embodiment of the present invention;

FIG. 8 is a bottom view thereof;

FIG. 9 is a top view thereof;

FIG. 10 is a back view thereof;

FIG. 11 is a front view thereof; and,

FIG. 12 is a right side view, the left side view being a mirror image thereof.

The broken line showing of the cookware is for illustrative purposes only and forms no part of the claimed design.
